CLAIM

The ornamental design for a tool tray for automotive repair, as shown and described.

DESCRIPTION

FIG. 1 is a perspective view of my tool tray for automotive repair showing the bottom, a first side and a first end thereof with the retractable tray within its casing;

FIG. 2 is a perspective view thereof showing the top, a second side and a second end thereof;

FIG. 3 is a view similar of FIG. 1 showing the bottom, first side and second end;

FIG. 4 is a perspective view of the retractable tray removed from its case showing the top, a second end and a first side thereof;

FIG. 5 is a perspective view of the retractable tray showing the bottom, second end and second side thereof; and,

FIG. 6 is an elevational view of the first end of the tray.
